UNITED STATES PATENT OFFICE

MAX HALL, OF STUTTGART, GERMANY, ASSIGNOR TO ROBERT BOSCH AKTIENGESELLSCHAFT, OF STUTTGART, GERMANY

ELECTRICAL IGNITION SYSTEM FOR INTERNAL COMBUSTION ENGINES

Application filed June 29, 1928, Serial No. 289,166, and in Germany July 14, 1927.

In internal combustion engines fitted with an electric starter, the accumulator battery connected to the dynamo usually has a voltage of 12 volts, and under certain circumstances even 24 volts. If electrically heated incandescent wire plugs are used for ignition, particularly on starting, and these are connected up to such accumulators, it is necessary to insert in the accumulator circuit 10 a resistance in series with the incandescent-wire owing to their low resistance, and this causes a considerable loss of energy from the battery during the discharge periods. In order to avoid this loss the incandescent-wire 15 plugs are, according to the invention, supplied from an additional accumulator, the voltage of which is lower than that of the accumulator battery provided for the starting motor, and which is connected to the dynamo through an automatic switch and a voltage reducing element.

Three forms of construction of the invention adapted for use on motor vehicles are shown in the accompanying drawings by way 25 of example.

Figure 1 shows the wiring diagram of a system having two automatic switches.

Figures 2 and 3 show the wiring diagrams of two different systems having a single automatic switch.

In Figure 1 the system consists of the dynamo 1, the starting motor 2, switch box 3, lead plate accumulator battery 4, supplying current at for example 12 volts potential, the two head light lamps 5 and the automatic switch 6 between the dynamo 1 and the switch box 3. An accumulator battery consisting of two Edison cells 9 connected in parallel, the average discharge voltage of 40 which amounts to 1.2 volts, is connected with the dynamo through a second automatic switch 7 and an incandescent lamp 8. Four incandescent wire ignition plugs 11 are connected to this battery 9, 9 through a hand-operated switch 10.

The incandescent lamp 8 reduces the voltage of the current supplied by the dynamo 1 to the value suitable for the two cells 9 and at the same time shows by glowing that the 50 cells 9 are charged.

The two Edison cells 9, automatic switch 7 and incandescent lamp 8 are preferably mounted on the side of the vehicle as a single unit.

The two automatic switches 6 and 7 in Figure 1, are replaced in Figure 2 by a single automatic switch 12, the armature 13 of which carries two contacts 14 and 15 separated by an insulated member 17. The contact 14 is connected with the switch box 3 and the contact 15 with the two Edison cells 9, whilst the common contact 16 is connected up with the dynamo 1.

Figure 3 shows a further system in which an ordinary automatic switch is used in conjunction with a switch box of the type usual in motor vehicle illumination. Two contacts 18 and 19 are provided in the switch box 3 on the lead passing from the automatic switch 6 to the main accumulator battery 4 and two terminals 20 and 21 are also provided therein, the terminal 20 being connected to the lead through the lamp 8 to the auxiliary accumulator 9, and the terminal 21 to the lead from the starting motor 2 through a starter press-button switch 22. Contact springs 23 and 24 are provided which are adapted to cooperate with the contacts 18 and 19. The two contact springs 23 and 24 are actuated by means of a cam 26 rotatable about an axis 25. In the open position shown, the two contact springs 23 bearing against the switch cam 26 are away from their respective contacts 18 and 19 so that the leads to both the starting press button switch 22 and also to the auxiliary battery 9 are cut out.

When the switch cam 26 is turned through 90°, the two contact springs 23 and 24 are forced against the contacts 18 and 19 and the engine can be started by depressing the starter button 22 after closing the incandescent plug switch 10. As soon as the engine has started, the starter button 22 is again released whilst the plug switch 10 for the incandescent wire plugs remains closed until the engine can run on self-ignition.

On stopping the engine the switch 25, 26 is turned back by hand to the position of rest shown, so that the main accumulator

battery 4 cannot discharge through the auxiliary accumulator 9.

This arrangement ensures that the auxiliary accumulator 9 can be charged while the engine is running. When the engine is at rest the glowing of the lamp 8 indicates that the switch 25, 26 must be turned off.

A single larger Edison cell or a lead plate cell may be used instead of the two Edison cells. When using the lead plate cell a suitable small resistance is preferably inserted before the incandescent wire plug owing to its slightly higher voltage.

I claim:

- 15 1. An electrical ignition system for internal combustion engines comprising in combination a dynamo, a starting motor, an accumulator battery and connections for charging said battery from said dynamo, a circuit for operating said starting motor from said battery, a plurality of incandescent-wire ignition plugs, an auxiliary accumulator of less voltage than the first mentioned accumulator battery, a circuit for energizing said plugs from said auxiliary accumulator, means to make and break said energizing circuit, and connections including an automatic switch for charging said auxiliary accumulator from said dynamo.
- 20 2. An electrical ignition system for internal combustion engines comprising in combination a dynamo, a starting motor, an accumulator battery and connections for charging said battery from said dynamo, a circuit for operating said starting motor from said battery, a plurality of incandescent-wire ignition plugs, an auxiliary accumulator of less voltage than the first mentioned accumulator battery, a circuit for energizing said plugs from said auxiliary accumulator, means to make and break said energizing circuit, connections including an automatic switch for charging said auxiliary accumulator from said dynamo, and a resistance in the connections between said auxiliary accumulator and said dynamo for reducing the charging voltage applied to the auxiliary accumulator and the incandescent wire plugs.
- 25 3. An electrical ignition system for internal combustion engines comprising in combination a dynamo, a starting motor, an accumulator battery and connections for charging said battery from said dynamo, a circuit for operating said starting motor from said battery, a plurality of incandescent-wire ignition plugs, an auxiliary accumulator of less voltage than the first mentioned accumulator battery, a circuit for energizing said plugs from said auxiliary accumulator, a circuit for charging said auxiliary accumulator from said dynamo, a pair of mutually insulated contacts connected respectively in circuit connections from said dynamo to said

lator battery, and a common automatic switch controlling said contacts.

4. An electrical ignition system for internal combustion engines comprising in combination a dynamo, a starting motor, an accumulator battery and a circuit for charging said battery from said dynamo, a circuit for operating said starting motor from said battery, a plurality of incandescent-wire ignition plugs, an auxiliary accumulator of less voltage than the first mentioned accumulator battery, a circuit for energizing said plugs from said auxiliary accumulator, a circuit for charging said auxiliary accumulator from said dynamo, a pair of mutually insulated contacts connected respectively in said second charging circuit and in a circuit connection from said first mentioned battery to said motor, a common automatic switch controlling both said charging circuits, and a key switch simultaneously controlling said insulated contacts.

In testimony whereof I have hereunto affixed my signature.

MAX RALL.
